UNITED STATES PATENT OFFICE

HUGH M. ROSS, OF RICHMOND HILL, NEW YORK, ASSIGNOR, BY MESNE ASSIGNMENTS, TO CROWN CORK & SEAL COMPANY, INC., OF BALTIMORE, MARYLAND, A CORPORATION OF NEW YORK

CONVEYER FOR BOTTLE SEALING AND FILLING MECHANISM

Application filed June 11, 1930. Serial No. 460,332.

This invention relates to bottle sealing and filling mechanism and more particularly to improved mechanism for automatically carrying bottles or containers into position for filling and sealing, for holding them in position during the filling and sealing operation and for thereafter carrying them away from the filling and sealing stations to a point where they may readily be crated or otherwise disposed of.

One of the objects of this invention is to provide mechanism of the character referred to which is efficient in operation and requires a minimum of skill and attention on the part of the operator.

Another object of the invention is to provide improved mechanism for adapting the machine for different size bottles or containers.

Other objects, novel features and advantages of the invention will be apparent from the following specification and accompanying drawings, wherein:

Fig. 1 is a front perspective view of a bottle filling machine embodying the invention;

Fig. 2 is a plan view of the feeding mechanism;

Fig. 3 is a section on the line 3-3 of Fig.

2;

Fig. 4 is a section on the line 4-4 of Fig.

2;

Fig. 5 is a section on the line 5-5 of Fig.

2;

Fig. 6 is a section on the line 6-6 of Fig.

5; and

Fig. 7 is a plan view of Fig. 5, with the cover plate removed.

Referring now to the drawings and more particularly to Fig. 1, the machine illustrated therein is composed of a base member 10 supporting mechanism for supplying syrup to bottles, for filling the same with water either plain or carbonated and for capping filled bottles. Syrup is supplied to the fill-

ing head 11 by suitable conduits (not shown). Caps for sealing the bottles are fed through the chute 12 into water filling and capping head 13. Power for operating the said mechanism embodied in the machine (which mechanism is not shown and described in detail since it forms no part of the present invention) is supplied from a motor 14 which drives a fly wheel 15 through the medium of a belt 16. Control of power to the mechanism may be accomplished through the medium of a hand wheel 17 operating a clutch or through a suitable clutch handle (not shown).

Bottles to be filled are presented under the syrup filling head 11 and water filling and capping head 13 by means of a conveyer supported by the table 18. At one end of the table 18 is provided a shaft 19 on which three superposed wheels 20 are rotatably mounted. At the other end of the table 18 there is provided a shaft 21 on the upper end of which are rotatably mounted three superposed wheels 22. The bottom wheel 22 rests on a plate 23 keyed to the shaft 21 and a plate 24 also keyed to the shaft 21 rests on the top sprocket 22 and is held in position by a bolt 25.

Two stub shafts 26 and 27 are journaled in the plates 23 and 24 and extend through apertures provided in the wheels 22. The upper end of the shaft 27 projects above the plate 24 and is shaped to receive a key. The shaft 27 is provided with gear teeth extending the full distance between the plates 23 and 24 and the shaft 26 is provided with gear teeth only over its lower half. Each wheel 22 is provided with a segmental rack 28, the racks for the upper and lower wheels meshing with the teeth of the shaft 27 while the rack for the middle wheel meshes with the teeth on the shaft 26. The wheels 20 and 22 are provided with uniformly spaced sockets 20^a and 22^a. An endless chain 29 is trained around each pair of wheels 20 and

22. Each chain is formed of links 30 having studs 30^a projecting through apertures in adjacent links. Each link also is provided with a perpendicular arm 31. The studs 30^a are adapted to be received in the sockets 20^a and 22^a and rotation of the shaft 21 by means later to be described causes movement of the chain. Between the wheels 20 and 22 there are provided guides 32 having 10 grooves in which are received the studs 30 for supporting the chains. The arrangement of the upper and lower wheels 22 is such that their sockets 22^a are always in vertical alignment. The position of the middle wheel may 15 be adjusted relative to the upper and bottom wheels 22 by rotation of the shaft 27, thus varying the spacing of the fingers 31 of the middle row with respect to the top and bottom rows. The fingers 31 define pockets 20 which receive the bottles to be filled and capped and by which the bottles are located accurately relative to the filling and capping devices. Guides 33 and 34 are provided to be engaged by the bottles to insure alinement 25 of the bottles with respect to the filling and capping mechanisms. These guides are adjustable to take care of different diameter bottles. Likewise, the spacing of the fingers 31 is adjustable to accommodate bottles of 30 different diameter. This adjustment is accomplished by means of the stub shafts 26 and 27 by which may be varied the angular relation of the middle wheel 22 to the top and bottom wheels. Although the width of 35 the pockets is varied the spacing between the center lines of the pockets remains unchanged.

The shaft 21 is intermittently rotated by means not described or shown in detail to 40 advance the feeding mechanism in step by step operation. Bottles to be filled and capped are supplied to the feeding mechanism by means of the conveyer 35 and pusher 36 and are delivered from the feeding 45 mechanism to a conveyer 37 which carries filled bottles to a crating or boxing station, not shown.

It is of course apparent that modifications may be made in the apparatus above 50 described, without in any way departing from the spirit of the invention as defined in the appended claims.

I claim:

1. In combination, a conveyer comprising 55 a plurality of superposed alined belts having fingers forming pockets, means for supporting and driving said belts, and means for relatively adjusting said belts in the direction of travel to vary the width of said 60 pockets.

2. In combination, a shaft, a plurality of 65 wheels rotatably mounted thereon, racks on said wheels, a pair of meshed pinions of which one meshes with certain of said racks and the other meshes with the remainder,

supporting means for said pinions keyed to said shaft, a belt passing around each wheel, and fingers carried by each belt.

3. In combination, a shaft, a plurality of 70 wheels mounted on said shaft, a belt passing around each wheel, fingers carried by each belt, means for rotating said wheels in unison, and means for adjusting the angular relation of said wheels.

4. In combination, an endless conveyer 75 comprising a plurality of superposed alined belts, each belt being composed of links having angular arms, means to actuate said belts in unison, and means to vary the relative position of the fingers of each belt in the 80 direction of travel.

5. In combination, a conveyer comprising a plurality of superposed alined belts composed of links having angular arms, means for supporting said belts, guide members 85 having grooves, and studs on said links slideable in said grooves.

6. In combination, a shell, a plurality of 90 wheels rotatably mounted thereon, racks on said wheels, a pair of meshed pinions of which one meshes with certain of said racks and the other meshes with the remainder, supporting means for said pinions keyed to said shaft, a belt fastened around each wheel, each belt being composed of links having 95 angular arms, guide members having grooves, and studs on said links slideable in said grooves.

7. In combination, a shaft, a plurality of 100 wheels mounted on said shaft, a belt fastened around each wheel and being composed of links having angular arms, guide members having grooves, studs on said links slideable in said grooves, means for rotating said wheels in unison, and means for adjusting 105 the angular relation of said wheels.

8. In combination, an endless conveyer 110 comprising a plurality of superposed alined belts, each belt being composed of links having angular arms, guide members having grooves, studs on said links slideable in said grooves, means to actuate said belts in unison, and means to vary the relative position 115 of the fingers of said belts in the direction of travel.

9. In combination, a conveyer comprising a plurality of superposed alined belts composed of links having angular arms forming pockets, means for supporting and driving said belts, means for relatively adjusting said belts in the direction of travel to vary the width of said pocket, guide members having grooves and studs on said links slideable in said grooves.

10. In combination, a conveyer comprising 125 a plurality of superposed alined belts composed of links having angular arms forming pockets, means for supporting and driving said belts, means for relatively adjusting said belts in the direction of travel 130.

to vary the width of said pockets, and guide members engaging said belts.

11. In combination, a conveyer comprising a plurality of superposed alined belts composed of links having angular arms forming pockets, means for supporting and driving said belts, means for relatively adjusting said belts in the direction of travel to vary the width of said pockets, and adjustable guide members defining a chute for articles arranged in said pockets.

In testimony whereof, I have signed my my name to this specification.

HUGH M. ROSS.
